UNITED STATES PATENT OFFICE

104,521

DESIGN FOR A PAPER CUP OR SIMILAR ARTICLE

Eliot P. Batchelder, Easton, Pa., assignor to
Dixie-Vortex Company, Easton, Pa., a corpora-
tion of Delaware

Application August 4, 1936, Serial No. 64,238

Term of patent 7 years

To all whom it may concern:

Be it known that I, Eliot P. Batchelder, a citizen of the United States, residing at Easton, in the county of Northampton and State of Pennsylvania, have invented a new, original, and ornamental Design for Paper Cups or Similar Articles, of which the following is a specification, reference being had to the accompanying drawing, forming part thereof.

In the drawing Figs. 1, 2 and 3 illustrate side elevations at different points in the circumference of the cup or similar article; and

Fig. 4 is a plan or development of the complete design as it is formed around the cup or similar article.

While I have illustrated my new design as applied to a cup it will be understood that the design is adapted to be embodied in similar or analogous articles of manufacture.

I claim:

The ornamental design for a paper cup or similar article as shown and described.

ELIOT P. BATCHELDER.
